COMPARTMENTED DISPENSING CONTAINER

Frank Mellion, Providence, R.I., assignor to Jo-Dee Corp., Warwick, R.I., a corporation of Rhode Island

Filed Apr. 1, 1965, Ser. No. 84,590

Term of patent 14 years

(Cl. D58—13)

F I G. 1

F I G. 2

F I G. 3

F I G. 4

FIG. 1 is a perspective view of a compartmented dispensing container showing my new design;

FIG. 2 is a top plan view thereof on an enlarged scale;

FIG. 3 is a front elevational view thereof on an enlarged scale;

FIG. 4 is a side elevational view thereof on an enlarged scale;

FIG. 5 is a rear elevational view thereof on an enlarged scale;

FIG. 6 is a bottom plan view thereof on an enlarged scale.

My compartmented dispensing container has the same appearance at both sides.

I claim:

The ornamental design for a compartmented dispensing container, substantially as shown and described.
